(Model.)

M. E. CARTWRIGHT.
PLAITING APPARATUS.

No. 406,086.

Patented July 2, 1889.

Attest,

*John S. Faro
Nat'l G. B. Dummard*

Inventor,

Mattie E. Cartwright

UNITED STATES PATENT OFFICE.

MATTIE E. CARTWRIGHT, OF ST. LOUIS, MISSOURI.

PLAITING APPARATUS.

SPECIFICATION forming part of Letters Patent No. 406,086, dated July 2, 1889.

Application filed April 13, 1889. Serial No. 307,126. (Model.)

To all whom it may concern:

Be it known that I, MATTIE E. CARTWRIGHT, a citizen of the United States, residing in the city of St. Louis, in the State of Missouri, have invented a new and useful Plaiting-Machine; and I do hereby declare the following to be a full, clear, and exact description of the invention, which will enable others skilled in the art to which it appertains to make and use the same.

The object of my invention is to provide a reliable and convenient means for making a certain kind of vertical plaiting, especially adapted for use in plaiting the skirts of ladies' dresses from the waist down their entire lengths, which in form, as well as in the manner in which they will open and close, resemble the folds of the bellows of an accordion, and which will retain their form without stitching. To make plaiting of this kind, uniform and reliable means should be provided for folding plaits of regular and uniform depth over and under very thin edges, and also for setting well the plaits thus formed by enabling both the upper and lower edges of the folds thus made to be readily, firmly, and thoroughly pressed on both sides through a damp cloth, and my invention affords a cheap, reliable, and convenient means of doing all this by hand within a reasonable limit of time, and the edge of the plait is sharp and clear-cut. I attain these objects by the mechanism illustrated in the accompanying drawings, in which—

Figure 1 is a perspective view of the under side of one section of the plaiting-machine. Fig. 2 is a perspective view of the device, showing a portion of the cloth plaited in condition for the reception of the second section of the device. Fig. 3 is a perspective view of one of the plaiting-strips. Fig. 4 is a perspective view of one of the clamps used to hold the fabric on the binding-strip. Fig. 5 is a cross-section on line 5 5 of Fig. 7, showing the cloth in place. Fig. 6 is an end view showing the two sections clamped together ready for reversing. Fig. 7 is a detailed top view of one end of the device, as shown in Fig. 2. Fig. 8 is a detail section showing the meeting of the binding-strips. Fig. 9 is a detail vertical section on line 9 9

of Fig. 7, showing the manner of securing the clamp-bar. Fig. 10 is a detail vertical section on line 10 10 of Fig. 7, showing the means for securing and releasing the slotted retaining-plates. Fig. 11 is a detailed end view of the finished product.

Similar letters refer to corresponding parts in all the figures.

A are two base-boards of greater length than the length of the plaits to be made and of any convenient and desired breadth, with plain smooth upper surfaces, and of exactly the same size and construction.

B are thin metallic binding-strips. I prefer strips of tin or steel. One of these strips is securely fastened in any suitable manner to one of the length edges of each base-board in such a manner that it will project above the inner surface of the base-board a distance equal to one-half of the width of the plaiting-strips.

C are slotted retaining-plates having notches a on the upper and lower edges exactly opposite each other to receive the clamp-screws D, working in the ends of the base-boards in nuts b, recessed into the wood near the ends of the boards, as shown in Fig. 10, so that the slotted retaining-plates can be clamped to the ends of the boards by the clamp-screws D, and the upper and lower edges of the slot will be in about the same plane as the inner surface of the base-boards when in place, and so that the edges of the binding-strips when the two boards are secured in place will be directly over each other. Any appropriate means may be employed for attaching and releasing the slotted retaining-plates from the base-boards; but I prefer the means described.

E are plaiting-strips of a length sufficient to extend across the entire length of the base-boards and through the slots in the retaining-plates at each end, as shown in Fig. 2, the slots in the retaining-plates being sufficient in width to allow the plaiting-strips, when in use and standing on edge on the inner surface of the boards, to pass freely through them.

F is a clamp-bar of uniform height with the plaiting-strips to clamp the plaiting-strips and plaiting formed about them firmly together for pressing, which passes freely

through the slot in one retaining-plate, in which it is secured by a washer *c* and a wood-screw *d*, as shown in Fig. 9, and having at the other end the metallic cap *e* with its threaded opening to receive the clamp-screw *g* passing into it through the slot in the other retaining-plate, as shown in Fig. 9. The clamp-bar may be worked adjustably between the retaining-plates in any suitable manner; but I prefer the mode described.

G are clamps to hold the material to the binding-strip.

H is the fabric to be plaited, and *I* is the fabric in place and ready to press.

15 To use my invention, take either of the base-boards with its binding-strip *B* fixed thereto, and clamp to each end a slotted retaining-plate *C* by means of the notches *a* in the edge of the retaining-plates and the 20 clamp-screws *D* in the ends of the board. The clamp-bar *F* is pushed to the outer edge of the board out of the way. One end of the fabric to be plaited is pulled over the base-board from the far side, a plaiting-strip is inserted next the binding-strip, and the edge of 25 the fabric is turned and clamped over the plaiting and binding strips thus brought together with clamps *G*, as shown in Fig. 2. A plaiting-strip is then put in on edge over the 30 fabric, so that it passes across the length of the board and through the slots of the retaining-plates at each end of the board. It is then pulled against the plaiting-strip first inserted, and the cloth is drawn under it until 35 it rests tight between the first strip and the last strip inserted, and the plaiting-strip last inserted rests throughout its entire length on the inner surface of the board with the fabric under it. Another plaiting-strip is then run 40 in under the fabric and drawn forward against the strip last placed with the fabric between them, and the fabric is then drawn tightly over the strip last inserted. Other plaiting-strips are then put in, first one over 45 and then one under the fabric, and each strip as inserted is pulled back against the one previously placed and the cloth drawn tightly under or over each of them, as before, and this is continued until the board is full or 50 the plaiting required is done. The clamp-bar *F* is then pulled firmly and evenly forward against the work done, and there clamped by means of the clamp-screw *g* to retain it there for pressing. When this is done, the clamps 55 *G*, which secure the fabric to the binding-strip, are removed, and the upper surface of the plaiting is then pressed through a damp cloth. The other board, with its binding-strip fixed thereto, is then placed over the 60 board containing the work pressed on one

side, inner surface downward, so that the clamp-screws in its ends will enter the notches *a* in the upper edge of the retaining-plates on the ends of the board containing the partly-pressed work, and the binding-strip on 65 the one board will be directly over that on the other. The clamp-nuts on the upper boards are then clamped and the boards reversed, so that the bottom board will be on top. The clamp-screws in the board now uppermost, on which the work was done, are unclamped, releasing the slotted retaining-plates from that board, which then can be and is lifted off, leaving the strips and partially-finished work firmly attached to the other 70 board with what was originally the under side of the work uppermost and ready for pressing on that side, and that side is then pressed in the same manner as before. The plaiting is then finished, and the clamp-bar *F* is unclamped and the strips withdrawn, leaving the plaiting free from the machine. If more plaiting is required than that finished at one time, the plaited portion is pulled over the binding-strip on the front of the base-board, 75 a plaiting-strip is run under the cloth and pulled against the inner surface of the binding-strip, and the last plait of the finished product is then placed over the plaiting and binding strips thus brought into juxtaposition 80 and clamped over them, and the plaiting of the fabric is then continued as before, pressed, and reversed and pressed as before.

Having fully described my invention, what I desire to claim and secure by Letters Patent 95 is—

1. In a plaiting-machine, thin metallic plaiting-strips, in combination with a base-board having a binding-strip on one edge, slotted retaining-plates on the ends of the base-board 100 to secure and retain the plaiting-strips, and an adjustable clamp-bar working on and lengthwise of the base-board, all substantially as described.

2. In a plaiting-machine, thin metallic plaiting-strips, in combination with two base-boards of exactly similar size and construction, each with a binding-strip on a corresponding edge, slotted retaining-plates, means of securing the retaining-plates to or releasing 110 them from the ends of both or either base-board whenever desired, and an adjustable clamp-bar working in the slot of the retaining-plates lengthwise of the base-board, all substantially as described, and for the purposes 115 specified.

MATTIE E. CARTWRIGHT.
